UNITED STATES PATENT OFFICE.

WILLIAM T. HENDERSON, OF SAN ANTONIO, TEXAS.

EYEGLASS-MOUNTING.

1,367,966.

Specification of Letters Patent.

Patented Feb. 8, 1921.

Application filed July 1, 1919. Serial No. 308,024.

To all whom it may concern:

Be it known that I, WILLIAM T. HENDERSON, a citizen of the United States, residing at San Antonio, in the county of Bexar and

5 State of Texas, have invented certain new and useful Improvements in Eyeglass-Mountings, of which the following is a specification.

The present invention relates to improvements in mountings for eye-glasses, and consists in certain improvements and changes made in the eye-glass mounting shown and described in my prior Patent No. 1,259,015 granted March 12, 1918.

10 15 The chief object of this invention is to provide an improved mounting in which the nose clamps are made in separate pieces from the guard arms that support them, as this construction is productive of many advantages, among which might be enumerated the following:

First, the nose clamps are apt to become worn out, corroded or broken, while the guard arms still remain intact, so that where 20 25 both the guard arms and nose clamps are made in one piece, the guard arms would have to be discarded. This involves a useless expense and by my invention I am enabled to further use the guard arms by removing the worn out, corroded or broken nose clamps and attaching new clamps to the same guard arms.

Second, by making the two parts separate the guard arms may be manufactured 30 35 of some rigid material that is cheaper and more easily procured than the resilient material out of which the nose clamps must be made.

Third, guard arms as now made in one 40 45 piece with the nose clamps being of resilient material are apt to be bent and distorted when clamped violently in the act of applying the glasses to the nose.

These and other disadvantages are removed by so constructing these parts that the guard arms may be made separately out of rigid material and the nose clamps attached thereto.

With the foregoing and other objects in 50 55 view which will become apparent to those skilled in this art, the invention consists in the constructions, combinations and arrangements of parts hereinafter described and claimed.

55 In the drawings, Figure 1 is a view in elevation, with parts

broken away, showing an improved mounting constructed in accordance with the present invention.

Fig. 2 is a plan view also with parts 60 broken away.

Fig. 3 is a perspective view showing parts involving this invention as detached.

Referring more particularly to the drawings, 1 designates the lenses having the rims 65 2, to which the lens clamps 3 are attached. The usual bridge piece is indicated at 4, which is connected to the lens clamps 3 by the posts or screws 5. These parts may be of the usual construction.

70 75 Fig. 3 shows the improvements in the detached positions, wherein 6 designates the lever formed with the enlargement 7 having a perforation 8 adapted to fit about the post or screw 5, the portion 7 being enlarged to provide an extensive bearing surface on which the lever may turn. At 9 appears the finger piece by which the lever is made to turn on the post or screw 5. This finger piece 9 extends from one end of the lever, 80 the other end of said lever being bent or twisted as shown at 10 in order to bring the smaller thickness of the lever end into a vertical position to better withstand the strain imposed thereon by the weight of the 85 guard arm and nose clamp.

90 95 The outer end of the twisted portion of the lever is formed into a loop 11 extending in a horizontal direction and from the free end of the loop depends the guard arm 12. The loop 11 is desirable to facilitate manufacture and it enables the guard arm to be carried outwardly from the lever in a position best suited to supporting the nose clamp.

95 100 105 The lower free end of the guard arm 12 is provided with holes 13 for the passage of the rivets 14 or other fastening means. These rivets 14 also pass through openings 15 made in the lower end of the nose clamp, which as shown is constructed of long and short arms 16 and 17 respectively, the short arm being preferably bent toward the long arm and having its upper portion resting against the long arm for purposes of strength and to bring the arms into proper positions for holding the nose pads 18. The arms 16 and 17 have enlarged heads as shown with perforations 19 to receive the rivets or other fastenings 20, which pass 110 through similar perforations in the nose pads 18.

Springs 21 are passed about the posts 5 and have their opposite ends engaging respectively against the lens clamps 3 and the levers 6, as shown in Fig. 2, such springs 5 serving to yieldably hold the levers and guard arms in such position as to cause the nose clamps to bind against the sides of the nose.

Stops 22 formed on the enlarged portions 10 7 of the levers are arranged to abut against the lens clamps 3 to limit the movements of the parts.

In use the parts are assembled as shown in Figs. 1 and 2 and the levers may be swung 15 about the pivots 5 by grasping the two finger pieces 9, this being the usual operation to separate the nose clamps in order to admit the nose therebetween. When the finger pieces are released after the device is adjusted to the nose the springs 21 will return 20 the levers in the opposite direction and result in binding the nose clamps tightly against the sides of the nose.

From the foregoing it will be understood 25 that the levers and guard arms are made separately from the nose clamps 17, which enables me to construct these parts out of different materials suitable to the functions of each. The nose clamps are intended to be 30 made out of spring metal to give them the required yielding pressure against the nose, but this material is expensive and apt to become corroded, worn and broken, in which event the nose clamps may be removed from 35 the guard arms and discarded. The rivet fastening forms a convenient means whereby detachment and attachment of the nose clamps may be effected.

On the other hand the levers and guard 40 arms may be made out of some cheaper material that is rigid and not so apt to be distorted when the finger pieces 9 are violently gripped.

I desire it to be understood that various changes may be made in the constructions, 45 combinations, and arrangements of parts herein described, provided such changes fall within the scope of the appended claims.

What is claimed is:

1. A mounting for eye-glasses comprising 50 lens clamps, a bridge, posts connecting said lens clamps and bridge, levers pivoting about said posts, rigid guard arms depending from said levers, resilient nose clamps composed of long and short arms secured to said guard arms, and pads secured to the long and short arms of said nose clamps. 55

2. A mounting for eyeglasses, comprising rigid guard arms, resilient nose clamps formed from a metal strip bent U shaped 60 and having enlarged heads at the free ends thereof for two point engagement on a nose, said clamps being detachably secured to the guard arms at the bends of the U, and nose pads on the enlarged heads of said clamps. 65

3. In an eyeglass mounting, the combination with lens clamps and a bridge, of posts connecting said clamps and bridge, laterally extending levers centrally pivoted on said posts, angularly disposed handles at one 70 end of said levers, and integral therewith, open loops on the opposite ends of the levers and integral therewith, rigid guard arms depending from said loops and flared at their lower ends, substantially U shaped nose 75 clamps formed of resilient material and detachably mounted on said guard arms with the bend of the U at the flared ends of the arms, said clamps being sprung outward from the arms, nose pads detachably mounted on the upper ends of said clamps, springs between said lens clamps and levers, and a stop on each of said levers to limit movement thereof. 80

In testimony whereof I affix my signature. 85

WILLIAM T. HENDERSON.
